VERTICAL SLAT VENETIAN BLIND SPACING

Andrew J. Toti, Modesto, Calif.

Application May 10, 1954, Serial No. 428,578

5 Claims. (Cl. 160—173)

This invention relates to Venetian blinds of the type 15 wherein the slats hang vertically from their upper ends, each from a carrier movable along a horizontally extending track from a position with the slats spaced, to a position with the slats bunched close together at one end of the track, and which slats may also be turned to any desired degree from the slats extending at right angles to the track, or at a slanted angle to close the spaces between them.

The present improvement has to do with means for positively controlling the spacing of the slats to maximum without using a spacing tape or cord for this purpose as heretofore, and which through shrinkage, stretching, and breaking from constant folding and unfolding has heretofore been a troublesome feature of such vertical slat blinds which is overcome by the improvement described herein, and several forms of which are shown in the drawings accompanying this specification.

In the drawings:

Fig. 1 is a bottom plan view of several of my improved vertical slat suspending carriers shown in endwise engaging relation and as pulled out as far as they will go to give maximum separation to any slats suspended therefrom.

Fig. 2 is an edge view of the carriers of Fig. 1 also in horizontal extension and with the slats in position on the supporting hanger rings or loops of the carriers.

Fig. 3 is an edge view of the carriers shoved together showing their overlapping relation when the slats are drawn together as by the pull cord, the cord not being shown.

Fig. 4 is a view of the extreme end of the last carrier to the right of Fig. 1.

Fig. 5 is a cross section of an arched overhead traverse track showing a master carrier riding on the confronting edges of the track.

Fig. 6 is a bottom view of the master carrier which suspends the last slat of a series, and receives several regular carriers, and to which master carrier the pull cord is attached to pull it along the track either way to open or close the blind as a whole.

Fig. 7 is a view of the right end of the master carrier showing several regular carriers attached within it.

Fig. 8 is a central longitudinal cross section of Fig. 6 taken along the line 8—8 thereof, and showing the pull cord securing clips.

Fig. 9 is an end view of Fig. 8.

Fig. 10 is a perspective view showing a few carriers in partially extended engagement, of a slightly different design from those of Fig. 1.

Fig. 11 is an end view of one of the carriers of Fig. 10 shown in engagement with the confronting edges of the traverse track.

Fig. 12 is a perspective view of a still further modification of a carrier with extending tongue to engage the next carrier and showing a portion of the upper end of a slat suspended from a ring formed on the carrier.

Fig. 13 is a perspective view showing a few of the car-

2

riers of Fig. 12 in end to end engagement as they would be when supported on a traverse track.

To give a clear understanding of the invention so that the detailed description of the drawings will be clear, it 5 may be said that there are numerous ways of sliding and turnably suspending the slats of the vertically extending slat type of Venetian blind, and that one way is to provide a horizontally extending overhead track like an inverted U fitted with small carriers or sliders grooved at 10 opposite sides to slidably engage the confronting edges of the inverted U-shaped track, with each carrier suspending one slat from its upper end by a link or other device, and the carriers are connected together by a flexible cord or tape, or chains, to limit their separation from each other, and as these cords stretch and shrink and wear out from constant flexing, the present invention was devised to dispense with tapes or the like for the above purpose and provide an extending tongue of sheet metal or its equivalent from each carrier which will engage the next adjacent carrier to definitely limit the separating distance of the carriers yet permit them all to be pushed close to one another, with the tongues automatically assuming an overlapping assembly when so moved. The sheet metal or the like connection between the carriers may take various 20 forms, some of which are shown in the drawings, and any of which also have a stabilizing effect on the carriers on the track since one being connected to the next one and so on the carriers cannot individually become twisted to jam on the track as short individual carriers often do, and this being the case each carrier may have but a very small contact with the track and hence pull along or slide much easier without resort to the use of small rollers as sometimes done on sliders used for supporting heavy drapes and portiers.

25 In Figs. 1 to 7 each carrier or slider and its extension tongue is formed as a unit of sheet metal or plastic, an elongated body 1 being the tongue and a bent down portion 2 being considered the carrier formed with a ring 3 or loop to which a link 4 suspends a vertical Venetian blind slat 5. In the present showing the suspending rings 3 are bent at an angle of about 45 degrees to suit the operation of turning the slats on their vertical axes as shown in my copending patent application filed under Serial 300,064 on date of July 21, 1952, but the particular suspension device need not be slanted, nor even be a ring or loop, but may be any device to suspend a vertical slat as variously shown in the art, as the present invention is concerned principally with the extended mutual positive engaging construction of the sliders or carriers to form positive limit stops to their separation.

30 Each extension or tongue 1 has a hook 6 formed on its extreme end and which hook has a neck 7 fitting easily in a slot 8 of the adjacent carrier tongue and overlapping the margins of the slot as indicated at 6 in Fig. 1 so as to prevent disengagement unless one carrier is twisted at 90° to pass its elongated hook through the slot of the next carrier.

35 Between the portions 1 and 2 notches 9, 9, are formed to receive the confronting edges 10, 10, of a hollow channel-like track 11 which extends horizontally to carry the weight of the blind and permit transverse movement of the carriers and their slats to the bodily open and closed positions shown in Figs. 2 and 3 respectively. When the slats or carriers are all moved together, the tongues all 40 stack up in overlapping position as indicated in Fig. 3.

45 It is obvious from what has been described so far that if the slats of the blind were all hanging from the carriers as described, they could be manually pushed or pulled to open or closed position like a portier, or draw cords could be attached to either or both end carriers, for 50 operating them, but I prefer to provide a master carrier at, at least one end of the series of slats and to

which the pull cord is attached and which master carrier is attached to the end carrier and itself slides bodily and freely within the hollow track. This is shown in Figs. 5 and 6 where the master carrier is designated 12 and it is formed with one slat suspending ring 3' and the first connecting regular carrier is hooked to it or secured to it as by cotter pin 13. The master carrier 12 is hollow or tubular and receives several regular carriers 1 which automatically stack up inside of it as indicated in Figs. 6 and 7 when the slats with their carriers are drawn close together.

The control cord 15 for pulling the master carrier bodily back and forth passes through two spaced clips 16 on one side wall of the master carrier and makes a bend 17 around an offset hook 18 which is pinched tightly around the cord. The cord also passes over pulleys at the extreme ends of the series of slats for controlling the movement of the slats in a manner well known in the art, hence not shown in the drawings.

In the modified forms of the connecting carriers shown in Figs. 10 and 13 the first shows the tongues 19 much narrower than those of Fig. 1 and both their free ends simply made hooked as at 20 to hook over a guiding loop 21 formed on the track engaging end 22 which is broader than the tongues, and also forms part of the notches 9 (see Fig. 11) which engage the confronting edges 10-10 of the track 11.

The form shown in Fig. 13 is similar to that of Fig. 10 but the tongues 22 are offset downwardly at 23 and formed with laterally extending lips 24 loosely engaging under the next tongue 22 to slidably engage the same. In the perspective view Fig. 12 the notches 9 which engage the traverse track are clearly shown and also the doubling over of the sheet metal at 25 to get rounding edges to ride along the upper and lower margins of the confronting edges of the track. In the construction shown in Figs. 1 and 2 a similar sliding contact is secured by forming rounding indentations on the carriers as at 27 and 28 to slide more easily on each other as well as on the track.

Having thus described several forms of the improvement and the operation of the invention it will be evident that it may be modified considerably within the spirit of the invention and as embraced within the scope of the appended claims.

I therefore claim:

1. In a vertical slat blind of the character described; an overhead horizontally disposed slotted track formed with confronting edges, slat carriers engaging said track edges for moving therealong, said carriers provided with a portion projecting downwardly through the slot to form a slat suspension connection, and each carrier provided with a stiff sheet material tongue above the slot and extending therealong in sliding engagement with the next carrier in overlying contact with its tongue.

2. In a vertical slat blind of the character described, an overhead horizontally disposed slotted track formed with confronting edges, slat carriers engaging said track edges for moving therealong, said carriers provided with a portion projecting downwardly through the slot to form a slat suspension connection, and each carrier provided with a stiff sheet material tongue above the slot and extending therealong in sliding engagement with the next carrier in overlying contact with its tongue, said tongues

each provided with guiding means slidably aligning it with the tongue below it, and limiting its withdrawal therefrom.

3. In a structure as set out in claim 2 said portion projecting downward through the slot provided with opposite open notches respectively receiving the confronting edges of the track, and further formed with lateral extensions riding on top of the track.

4. In a structure as set out in claim 2 a special carrier at the end of a series of the carriers provided with means for securing an operating cord thereto, and provided with a hollow elongated body arranged to receive several of the succeeding carriers therein in telescopic relation.

5. In a structure as set out in claim 2 said portion projecting downward through the slot formed with a ring-like loop extending downward at an angle away from the carrier.
